C. G. DEAN.
MEANS FOR OPERATING EXPLOSIVE ENGINES.
APPLICATION FILED AUG. 19, 1907.

910,181.

Patented Jan. 19, 1909.

UNITED STATES PATENT OFFICE.

CHARLES G. DEAN, OF INDIANAPOLIS, INDIANA.

MEANS FOR OPERATING EXPLOSIVE-ENGINES.

No. 910,181.

Specification of Letters Patent.

Patented Jan. 19, 1909.

Application filed August 19, 1907. Serial No. 389,284.

To all whom it may concern:

Be it known that I, CHARLES G. DEAN, a citizen of the United States, residing at Indianapolis, in the county of Marion and State of Indiana, have invented certain new and useful Improvements in Means for Operating Explosive-Engines; and I do declare the following to be a full, clear, and exact description of the invention, reference 10 being had to the accompanying drawings, and to the letters and figures of reference marked thereon, which form a part of this specification.

This invention relates to engines that are actuated or energized by explosions of gaseous fluid, more especially stationary piston engines in which an explosion is produced for each revolution of the engine-shaft, the invention having reference particularly to 15 methods of producing and exploding the fluid in the engine for energizing its mechanism, and to means for automatically controlling the temperature of the explosion chest to prevent premature explosions.

Objects of the invention are to provide an improved, convenient and relatively inexpensive method of producing the gaseous fluid from hydrocarbon oil, and a convenient, inexpensive method of governing the 20 explosions of the fluid under varying conditions of operation, a further object of the invention being to provide improved means whereby the fluid may be produced and exploded at the minimum cost; a still further 25 specific object being to provide an improved explosion-chest for explosive engines adapted to be constructed cheaply and whereby the highest efficiency may be attained in operation, to the end that explosive engines 30 may be operated most economically and reliably and by unskilled attendants.

The invention consists in a new and useful method of producing gaseous fluid in explosive engines for their operation; a new 45 and useful method of exploding the fluid in the engines for energizing the mechanism thereof; in an improved explosion chest for the explosive engine, and in novel accessories to the explosion-chest to modify action 50 thereof under varying atmospheric conditions. And the invention consists further in the novel elements and combinations and arrangements of elements or features, as hereinafter particularly described and pointed 55 out in the claims forming parts of this specification.

Referring to the drawings, Figure 1 is a sectional view of an explosive engine of simple form having the improved features of construction substantially in accordance 60 with the invention and illustrating the means whereby the methods are carried out; Fig. 2, a fragmentary sectional view of the engine cylinder having the improved explosion-chest connected thereto and shown 65 in central vertical section, as on the plane of the line A A in Fig. 3; Fig. 3, a horizontal sectional view of the improved explosion chest approximately on the line B B in Fig. 1; Fig. 4, a fragmentary sectional view 70 similar to Fig. 2, but with several parts in different positions, and, Fig. 5, a fragmentary vertical sectional view approximately on the line C C in Fig. 3.

Similar reference characters in the different figures of the drawings designate like parts or features.

In the drawings *a* designates an engine frame; *b*, the cylinder of the engine having one cylinder head *b'* and an exhaust port *c*; 80 the wall of the cylinder having a chamber *d* through which water may circulate for cooling the cylinder in operation; *e*, designating the piston movable in the cylinder; *f*, the crank-shaft, and *g* the connecting rod or pitman which connects the piston with the crank-shaft.

The engine is provided with an air pump comprising a cylinder *h* having an inlet port *h'* and suitably mounted fixedly preferably 90 against the engine cylinder, the pump having a piston *i* movable therein so as to open the port *h* on its out-stroke, there being a connecting rod *j* connected to the piston and also to an eccentric strap *k* that is mounted 95 on an eccentric *l* which is secured to the shaft *f*. The pump cylinder is closed at one end and is open at its opposite end.

An oil reservoir *m* is arranged near the engine and may be of any suitable construction 100 for holding oil, from which the gaseous fluid is to be produced.

The improved explosion chest comprises a side wall *n*, a bottom *n'* and a top portion *n''*, all cast preferably integrally and suitably attached securely to the head *b'* of the cylinder, there being a passageway *o* between the explosion chest and the cylinder, and a vertical barrier *p* or deflector extending up from the bottom *n'* adjacent to the passageway *o* to deflect the vapor charges and prevent the flow 110 of oil from the bottom of the explosion chest

into the passageway, there being ample clearance above the barrier for free communication between the interior of the main portion of the explosion chest and the cylinder. The interior of the explosion chest has a suitable number of projections adapted to become heated by repeated explosions to a high degree so as to aid in gasifying the vapor charges and help to cause ignition of the explosive mixture, each one of the projections preferably being in the form of a thin vertical wing q projecting from the side n towards the barrier p and two oppositely disposed wings s and t extending from different portions of the side between the projection q and the barrier. Suitable provision is made for preventing excessive heating of the internal projections or wings above-mentioned, so that the results of the explosions may be modified, and for this purpose the exterior of the explosion chest is provided with a suitable number of projections preferably formed as thin wings, or ribs s or t , extending outwardly from the side n and similar projections t which extend from the side and also up on the top portion n' , the projections being adapted to be cooled rapidly by the atmospheric air currents and therefore to dissipate heat from the wall of the explosion chest, all for a specific purpose as will further appear more clearly. A suitable vaporizer is connected in any suitable manner to the explosion chest and preferably comprises a main body part u and an air chest v suitably connected thereto, the body part having a vaporizer valve w seated in the end thereof that joins the explosion chest, the valve serving to prevent the return of fluid or gases from the explosion chest after having entered it or been produced therein. The valve has a stem extending through the body part u into the air chest v and has a spring x thereon for normally holding the valve w to the seat which is provided for it, and the body part u has an air duct y extending from the air chest v to a vaporizing chamber z in which air may be mixed with oil to be discharged as vapor past the valve w into the explosion chest. The body part u is provided also with an oil duct 1 which communicates with an inlet opening 2 but is normally closed by means of a combined check and throttle valve 3 suitably seated and having its movements or amount of lift governed by a screw stop 4 provided with a handle 5 to be adjusted with reference to an indicator 6 that is mounted on the air chest v to close the valve for stopping the engine and permit it to open for starting, there being an oil pipe 7 connected with the inlet opening 2 and also connected in a suitable manner to the oil reservoir m . An air pipe 8 is connected with the closed end of the cylinder h and also to the air chest v , so that the out strokes of the piston i may create vacuum in the air chest v to permit the valve 3 to lift and admit oil from the reservoir, the valve 3 performing the functions of a pump valve and preventing the return of oil to the reservoir.

When the engine is exposed to extremely cold atmosphere, as for instance, when not properly housed in winter seasons when the external projections of the explosion chest may radiate or dissipate more heat than is desired, the explosion chest is provided with a cover comprising a side wall 9 and a top portion $9'$ and suitably mounted on the cylinder head b' or otherwise supported as may be desired, so as to inclose the explosion chest with some space beneath the wall 9 to admit air into the cover when required. The top portion of the cover has a suitable open neck 10 provided with a lid 11 that is connected to the neck by a hinge $11'$. The side 9 of the cover is provided with a door 12 through which a torch light or lamp may be inserted in order to heat the side n of the explosion chest when it is desired to start the engine. A suitable guideway 13 is provided in the upper portion of the cover close to the hinge $11'$, and a rod 14 having a screw end 15 is screwed into the cylinder head b' and preferably provided with a nut lock 16 , the rod being composed of suitable highly expandible metal, such as brass. The upper end of the rod engages the lid 11 which will be closed when the rod is cold, and in operation the rod will expand and force the lid open more or less as may be predetermined, so that a flow of air will be induced through the cover which is designed to exclude the excessively cold atmospheric air from the projections s and t , and thus modifying the temperature to which the projections are exposed to accord approximately with prevailing summer temperatures.

Although the engine is represented as being of the vertical type, it will be understood that it may be constructed as a horizontal engine, and various modifications of the various parts may be fairly made within the scope of the invention.

In practical use as above indicated a flame will be applied to the side n and bottom n' of the explosion chest in order to temporarily heat the internal projections or wings, and the engine will be caused to move slightly so as to operate the air pump which will draw a charge of oil through the valve 3 , and with the inward stroke of the piston i air will be forced into the air chest v and through the duct y to the chamber z to mix with the oil which will flow through the duct 1 to the chamber z , the movement of the oil being accelerated by air passing past the stem of the valve 3 to the duct 1 . While the piston i is returning towards the head b' and causing compression in the explosion

chest, the air pressure caused by the air-pump will force the valve *w* open and vaporize the charge of oil and air that may have become mixed or partially mixed in the 5 chamber *z*, discharging the resultant hydro-carbon vapor into the explosion chamber to be gasified and ignited under compression by means of the heated internal projections or wings *q, r r'*, assisted by the heat due to 10 compression, the explosion producing the desired force for imparting motion to the piston *e*. The sizes of the oil charges may be changed or regulated by manipulating the handle 5 and the air charges will be 15 varied with a given speed of piston stroke of the air pump. When the load on the engine becomes reduced as may occur, the tendency of the engine will be to race, but it is almost immediately arrested by reason of 20 the explosion chest becoming heated to a higher degree with the slightly increased number of explosions and therefore the heat will be radiated or dissipated at a higher rate, thus quickly reducing the temperature 25 of the explosion chamber, and therefore the internal projections, so as to prevent premature ignition, and so that a perfect combustion may not occur and therefore the speed of the engine will be slightly reduced. 30 The repeated explosions obviously will increase the temperature of the internal projections, and this will be required to maintain the average rate of speed with the load now increased, but if the load is still decreased the governing of the speed will result as above-described. In some cases as hereinbefore indicated, the cover may not be required on the explosion chest but when used will automatically regulate the 35 temperature about the explosion chamber as a result of the varying temperatures expanding and contracting the rod 14 to operate the lid 11 of the cover.

It will be observed that the explosion chest 45 has large capacity as compared with the cylinder area, and when the air pump blows a spray of oil and air into the explosion chest while the piston *e* is beginning to compress the scavenging air in the engine cylinder, the 50 mixture spreads out against the heated walls and the wings of the explosion chest and becomes gaseous by reason of the heat, so that when the air is forced from the cylinder and compressed in the explosion chest, the air 55 thoroughly mixes with the gaseous fluid, resulting instantly in the formation of perfect explosive mixture which ignites under compression by means of the hot wings and walls of the explosion chest. While it is designed 60 that the walls and wings of the explosion-chest shall become highly heated so as to produce the explosions, excessive heat would ordinarily develop, and therefore the external projections or other suitable means are relied

on to carry off surplus heat and thus modify 65 the results of heating the internal wings, thereby preventing premature explosions.

It will be understood that it is customary to provide explosive engines with governors to regulate the supply of oil for varying 70 loads, a greater supply of oil being required when the load temporarily increases, and in such cases the larger charges tend to raise the temperature of the explosion chamber excessively, but such higher temperatures 75 which would cause premature explosions are prevented by the external projections on the explosion chest.

Having thus described the invention, what 80 is claimed as new is—

1. In an explosive engine, an explosion-chest having an inlet opening and an outlet opening in different planes and having also a deflecting barrier on the interior of the wall thereof extending from the side that has the 85 outlet opening towards the opposite side and between the planes of the opening.

2. In an explosive engine, an explosion-chest having an outlet opening in the wall thereof and having also an inlet opening in a portion of the wall thereof remote from the outlet opening, a spraying device in the inlet opening to direct a spray into the explosion-chest remote from the outlet opening, and a plurality of wings on the interior of the wall of the 95 explosion-chest remote from the outlet opening and within range of the spray.

3. In an explosive engine, an explosion-chest having an inlet opening and an outlet opening in different planes, a barrier extending from the bottom of the explosion-chest 100 between the planes of the openings, and projections on the interior of the wall of the explosion-chest at one side of the barrier near the inlet opening.

4. In an explosive engine, an explosion-chest having an inlet opening in the upper portion and an outlet opening in the lower portion thereof in different planes, a plurality of wings on the interior of the wall of 110 the explosion-chest at one side of the plane of the outlet opening, and a plurality of projections on the exterior of the explosion-chest and extending laterally from the sides and vertically from the top thereof, portions of 115 the wall having wings on the interior and a relatively greater number of projections on the exterior thereof.

5. In an explosive engine, the combination with a cylinder and piston, a piston-rod and shaft, and an air-pump operated by the shaft, of an explosion-chest having an outlet opening connected with the cylinder and having also an inlet opening arranged in the wall thereof remote from and not opposite the 120 outlet opening; a vaporizer body connected to the explosion-chest at the inlet opening thereof, a vaporizing valve seated in the vaporizer 125

body and normally closed; a spring holding the valve in normal position, an air-conduit between the air-pump and the valve, an oil-conduit extending to the valve, a plurality of 5 wings on the interior of the explosion chest in proximity to the vaporizing valve, and a plurality of projections on the exterior of the explosion-chest and extending from the sides thereof and vertically from the top thereof, 10 portions of the wall of the explosion-chest

having wings on the interior and a relatively greater number of projections on the exterior thereof.

In testimony whereof, I affix my signature in presence of two witnesses.

CHARLES G. DEAN,
